[57] CLAIM

The ornamental design for a disposable vehicle seat shield, as shown.

DESCRIPTION

FIG. 1 is a perspective view of a disposable vehicle seat shield showing our new design;
FIG. 2 is a front view thereof;
FIG. 3 is a rear view thereof;
FIG. 4 is a top view thereof;
FIG. 5 is a bottom view thereof;
FIG. 6 is a left view thereof; and
FIG. 7 is a right view thereof.

The broken line showing of an automobile seat is environmental only and forms no part of the claimed design.
